UNITED STATES PATENT OFFICE.

FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

WROUGHT-METAL TYPE-BAR.

No. 919,239.

Specification of Letters Patent.

Patented April 20, 1909.

Application filed April 18, 1901, Serial No. 56,481. Renewed March 10, 1909. Serial No. 482,572.

To all whom it may concern:

Be it known that I, FRANCIS H. RICHARDS, a citizen of the United States, residing at Hartford, in the county of Hartford and 5 State of Connecticut, have invented certain new and useful Improvements in Wrought-Metal Type-Bars, of which the following is a specification.

This invention relates to typebars and 10 their manufacture and it has for its main object the provision of a wrought metal typebar formed from wrought metal, and adapted for use in the typographic art.

The most satisfactory wrought-metal 15 typebar, that is, a bar whose edge is provided with a series of consecutive wrought types spaced in accordance with the usual and customary spacing subsisting in the 20 typographic art, is the product not only of material capable of being worked into exact, compact and unbroken counterparts of the type-forming dies, but each individual 25 type-forming operation should have been confined to that portion of the edge of the blank under and immediately adjacent to 30 the working die, and, furthermore, the material in each particular portion or section in excess of what is needed to form a type-block and its various faces shall have been 35 disposed of without detriment to the contiguous type or type faces. The making of a 40 satisfactory wrought-metal typebar involves, accordingly, something more than the mere repetition of an operation which, 45 in itself, might be capable of forming a single type removed in position from proximity to a finished type or type face.

In forming from cold metal blanks, types 40 suitable for use in the typographic art by a wrought process, the field of action during 45 the shaping of any individual type is necessarily small and all of the operations which may be necessary to produce a finished type are also conducted upon a small scale. For 50 these reasons it is even more important that the material operated upon should be the best that it is possible to obtain for the purpose. When the body of metal to be subjected to treatment is itself minute, the 55 imperfections that would not be considered in operating upon a large amount of metal become of vast importance and if not eliminated would frequently result in the production of an almost, if not quite, worthless type, for the purpose which it is intended to

serve. It is for this reason that the imperfections incident to types formed on cast metal constitute imperfections which it is desirable to eliminate in order to assure at all times the formation of perfect types and 60 the production of perfect impressions from said types. In order to obtain these superior results it is necessary to make use of a material having a structure as nearly homogeneous as it is possible to obtain, and 65 a cast metal, however good it might be, will not meet the requirements.

In carrying out the operations for producing the bar the subject of my present improvements I employ a blank which has 70 been wrought into a homogeneous structure and in which the metal is thoroughly condensed, having substantially no loosely held particles to crush or crumble, when subjected to compression by a die. 75

There has been no general recognition of the fact that a continued rectilinear movement of a die into a mass of suitable material coextensive with the duration of type-forming, is ineffectual in practice to completely and absolutely fill the die. This mode of type-forming, results therefore in a type, the edges of whose impression surfaces are lacking in sharpness and definition. 80

In producing my improved typebar I make 85 use of a blank condensed and rendered of a homogeneous structure, by methods which operate to produce a wrought blank and which possess such characteristics as best fit it to be operated upon by the type-forming die. The blank or bar of metal employed in the preferred form of my invention is one 90 having a peculiar wrought structure, in that it is longitudinally wrought. I subject each type-formable portion of the blank to repeated actions, which, for the purpose of producing symmetrically-formed types, are preferably alternated from side to side of the mass. These repeated actions result in the gradual reduction of the type-block to 95 shape and are of such character that they operate to strengthen and finish the base portions of the block where the latter connects with the body of the typebar-blank, and to condense and compact the impression and 100 other faces of the type besides operating to satisfactorily fill the angular portion and hair-line spaces of the die cavity. These methods of manufacture, result in the production of my improved type and typebar 105 110

possessing superior qualities and capable of meeting the most rigorous demands of the typographic art.

In the drawings accompanying the following specification, Figure 1 is a perspective view representing a suitable device in a conventional way for producing a typebar-blank appropriate for producing my improved bar. Fig. 2 is also a perspective view 10 representing one method of forming a wrought type upon a typebar-blank. Fig. 3 is partly an elevational and partly a sectional view taken on a plane transverse to the blank and illustrates one form of a relative subsidiary movement imparted to the members during the process of forming a type on the 15 edge of the blank. Fig. 4 is a view similar to Fig. 3 representing the position of the parts immediately at the close of a type-making 20 operation and showing in a diagrammatic way the path traced by a die in approaching and receding from its type-forming position according to one construction for adjusting the same. Fig. 5 is an elevational 25 view representing a portion of a die-carrier, and the edge of a typebar-blank, the relation of the blank to the die-carrier in this figure being different from that set forth in Fig. 2. Fig. 6 is a perspective view 30 representing my improved typebar.

Similar characters of reference designate corresponding parts in all the figures of the drawings.

This invention embraces a typebar formed 35 from a wrought type-metal blank whose edge is provided with integral wrought-metal types. The blank upon which and from which the typebar are to be formed is wrought into the desired or appropriate size 40 and shape by a process or processes which will result in condensing and compacting most perfectly the material of the blank. Preferably the processes to which the material is subjected preliminary to the operation 45 of the type-forming dies upon its edge and to form a wrought-metal blank are such as to produce a wrought structure longitudinally of the blank—that is, the blank is one in which the fiber or grain extends length- 50 wise of the blank—as I have found a blank of this character is best adapted for producing wrought types of a superior quality. The material, in whatever way it is brought to a solid condition, is subjected to any of 55 the processes employed in the arts for producing wrought-metal and which are suitable to the present requirements; thus, for instance, the blank may be passed through a pair of rolls, designated in a conventional 60 way in Fig. 1 by B, B, the blank being designated throughout the present specification and drawings by H. It is not essential, however, for the production of this character of structure—that is, one in which the so-called 65 fiber extends in line with that edge of the

blank upon which the dies are to operate—that the material be passed between rolls, as substantially the same results may be produced by subjecting the metal to flowage—for instance, by forcing it through 70 a suitable die—as set forth in my application Serial No. 44,672, filed January 25, 1901. The blank may be of some material suitable for the purpose, for instance, type-metal of proper composition 75 which after subjection to a process for producing a homogeneous wrought structure may be utilized in the form of a continuous ribbon or rod or in the form of separate pieces each having a length substantially 80 equal to the length of the finished typebar. For the production of consecutive types on the edge of the blank each individual type-formable segment of the blank is, in producing 85 the typebar forming the subject of the present invention, subjected to operations that will result in the formation and finishing of a type prior to the transfer of these operations to the next segment in advance, and which has the metal both in the head 90 and in the body portion thereof thoroughly condensed and compacted substantially throughout the whole mass of the type. In order to produce this result I deem it necessary not only to condense the face portion of 95 the type but also to subject the body and the base of the progressively formed type-block, designated in a general way by F, to a direct compressing action which will result in condensing and more intimately uniting 100 the particles of the metal in the body and the base of such type-block. When a type-block is treated in this manner it will be evident that a type having a strong and stiff base and body will result, and the type will therefore be able to withstand successfully much greater crushing forces when in actual use than would a type having a compressed face and a body substantially uncompressed as compared with such face.

The principal operations to which each portion or segment of the typebar-blank will, when these are acted upon individually, usually be subjected in order to form a perfect wrought metal type are cutting or incising, rolling, swaging and forging, the rolling and swaging serving to get rid of the surplus material and to produce the smooth and compact impression face having sharply-cut contour, and the forging operation serving to produce compacted and condensed body portion and base of the type.

Two principal movements may with advantage be utilized in forming types on the solid blank to make the present typebar, one of such movements being a feed movement of the members together and the other a simultaneous and relatively small to-and-fro alternating movement. When these two movements are combined each type will be 130

formed gradually by repeated and progressive reductions and shapings of the type-formable material; that is, the block and impression face of the type will be gradually brought into their finished shape and the surplus stock will be gradually rolled off. Thus the type will be worked up step by step to its finished shape by easy stages and repeated compressions of the particles together, and there will be no sudden and violent disturbance of a large mass of the stock, as is the case where the whole top face of the head of the type is formed by a single and practically indivisible operation. Each type-block will, in the referred to method, be subjected, it is apparent, to a continuous operation, in the sense that each portion of the edge of the blank will be formed into a complete and finished type-block before any other portion of the edge is subjected to the action of a second die to form a consecutive type. The blank may be subjected to these repeated operations in any suitable manner, but while hand-operated tools may be employed for the purpose, suitable mechanism will ordinarily be used. Moreover, while different tools may be employed for forming the various faces of the type-block, I have deemed it preferable to make use of a single tool or die, for the reason before indicated, that when one of the co-operative type-making members is moved relatively to the other, a single die is sufficient to subject the material of the blank to all the various operations which it undergoes before becoming a finished type.

Any proper type-die may be employed, and this may be mounted in any desired manner—thus, for instance, I may support one or more type-dies, such as d , on a carrier, such as D , which carrier may be secured to a shaft, such as 2 , capable, at least, of a movement of rotation about its own axis, for the purpose of adjusting a die into its working position at the type-making point, and if desired this die-carrier may be mounted upon a rotary supporting-carrier, the path of a die when the carrier is rotating and revolving being evidently a cycloidal one, as indicated in Fig. 4.

The wrought-metal blank may be supported in any appropriate manner during the operation of the type-forming die, and in effecting the penetration of the material of the blank by the die it is immaterial whether the movement which I may designate as a transverse feeding movement is imparted to the blank or the die or to both, but I find it convenient to feed the blank against the die.

For the production of the relative to-and-fro motion I may so actuate the blank by imparting such motion to a work-holder in which the blank may be supported. Good results are obtained in the character of the

types produced by making this to-and-fro motion an oscillatory one about a given axis, although the present invention is by no means limited in its scope to the bar made by an oscillation about such an axis, as the to-and-fro motion may be of different character. Thus, for instance, instead of oscillating the blank, the die may be rocked to and fro through a small angle while in engagement with the blank, this being indicated by the dotted die outline d' , d'' in Fig. 4.

The rolling action to which the material is subjected during the formation of a type-block is effected ordinarily by means of a die, and a die construction which I find particularly advantageous in forming my improved wrought type is one that permits confinement of a given portion of a type-bar-blank endwise thereof and type-forming operations thereon by a device which operates as a single mechanical part and which may even be constructed in one piece, although it has many functions that might be carried out by a large number of tools. The die may be furnished with a wall or blade at one or both sides one located in advance of the type-die if a blade in this location is used constituting a space-forming die for displacing a narrow strip of the stock forward of the forming type, while the wall preferably present at the opposite side of the die operates to confine endwise of the blank the portion of the stock to be operated upon at any given time for the formation of a type. The type-dies shown herein each have both a space-forming die and a retaining wall, the former being designated by 5 and the latter by $5'$, which may both be of the same width, or the die which operates in advance of the die proper may be wider than the wall at the other side of the die for a purpose more fully set forth in my application Serial No. 57,934, filed April 29, 1901. This retaining wall forms means for confining endwise of the bar or blank the material within any given type field while such material is being wrought into shape, but as there are no corresponding end walls on the die to check the lateral flowage during compression the material will, of course, be free to flow out crosswise of the blank. Both the wall and the space-forming die project usually throughout their whole length beyond the outer surface of the die, and hence throughout the whole period during which a type is being formed the retaining wall serves to confine on one side the mass of material that is being shaped. The bottom of the die serves to roll out sidewise the major portion of material not required for the making of a type, while the bottom edges of the die serve to incise and draw inward from the mass of the blank sufficient material to fill the die-space and form a

115
120
125
130

finished type. That part of the edge of the typebar-blank which is operated upon but is not compressed by the space-forming die and is not contained within the die-space 5 is compressed by the faces of the lateral extensions 6, 6 provided for the purpose on the die and is rolled off sidewise of the typebar-blank, but is always confined endwise of the blank by the retaining wall just mentioned 10 which operates additionally to form the ultimate type-separating space. Hence none of the surplus material is operated upon in such a manner as to force it into the field of an adjacent type, but instead all of the excess, whether it is forced out by the edge 15 of the space-forming die or by the surfaces of the die-extensions, flows sidewise of the blank and may afterward be severed from the bar to bring the sides of the latter into 20 substantial parallelism with each other. Ordinarily the material forced out by the space-forming die and that which is rolled off by the die-extensions will to a considerable extent be moved outward during the 25 preliminary operation of forming a type, that is, when the die is rolled onto the edge of the blank and into working position. The amount of material displaced during this 30 preliminary rolling on of the die of course depends upon the extent to which the die penetrates the blank when it assumes its working position. The major portion of the work of forming a type may be effected during the time that the blank is oscillated and, 35 if desired, the whole type-forming period may be coextensive with that in which this oscillation is occurring.

The manner in which and the extent to which the type-formable material confined 40 endwise of the blank is operated upon are dependent upon the oscillation of the blank, and also upon the feed movement thereof. Usually a somewhat rapid feed movement will be imparted to the blank during the 45 early stages of the oscillation thereof, in order that the type may be roughed out rapidly and afterward finished somewhat more slowly as the work approaches completion.

The die is brought into its proper position 50 with relation to the blank by some suitable means operating or operative in a desired manner. In Figs. 2 and 3 the die-carrier is represented with its plane transverse to the direction of the length of the blank, and 55 after a selected die is brought into position over the blank and the two are brought into engagement the latter may be oscillated by suitable mechanism, this oscillation being indicated in a general way by the dotted 60 axial lines α , α' , converging to and passing through the axis of oscillation, which axis, I find, is best located in or immediately adjacent to the impression face of the finished type. The extreme position on one side and 65 on the other of the blank during its oscillation

is indicated in this figure by dotted outlines, while the rocking motion of the die if this be the member actuated is similarly indicated by the dotted lines α' , α' drawn normal to the die in its extreme positions, Fig. 70 75. Instead, however, of arranging the die-carrier with its plane transversely to the blank, the carrier may be disposed as in Fig. 5, in line with the blank, a similar oscillatory movement being imparted, as an instance of a relative to-and-fro movement, to the blank after a selected die has been brought into its proper position to operate upon the edge of the blank. As the blank is swung toward the left-hand and toward the 80 right-hand alternately (which particular operation is chosen as representing the general results attainable) and is simultaneously fed against the die, the stock at the base of the forming type-block is forged, 85 first at the left-hand side and then at the right-hand side, the forging action being greatest at the base of the type-block because this part of the latter is farthest from the axis of oscillation. The forging action, 90 however, extends up the entire length of the side being operated upon and results in a thorough compacting or condensing of the particles of the block. The forging action being the greatest at the base of the type-block, 95 the latter will be strengthened the most in the region of its base, and the strengthened base will be also connected with the face of the type by a layer of condensed metal thoroughly compacted by the 100 forging operation. At each swing of the typebar-blank toward one of its extreme positions material is forced up into the die cavity, while on the opposite side the space formed by the withdrawal of the side of 105 the type-block from the face of the die forms an outlet through which air confined between the type-block and the die may escape. Each time that a feed movement and an oscillation occur an additional portion of the 110 surplus material confined under the type-die proper is forced out sidewise of the blank by the lower edge of the space-forming die and by the die-extensions. According to the preferred mode of operation, the 115 oscillatory movement will decrease in extent or amount of its side to side movement and cease before the final completion of the type, and in order to fill the die completely and thus form a perfectly finished 120 type it is desirable to finish a type by a simple feed movement after the oscillations have ceased. At this time the die will operate principally as a means for swaging the face of the type to its finished 125 plane surface. After any one type has been shaped in substantially the same way, but the retaining wall 5 should be so located as to lie close beside the adjacent finished type 130

to the rear in order that the types when completed may be sufficiently close to one another.

The fins which are rolled off from the 5 sides of the blank by the die-extensions and by the edge of the space-forming die may be removed at any proper time and in any suitable manner, a pair of cutting tools, such as *c*, *c*, being indicated herein for the purpose, these preferably operating after the 10 series of types has been formed.

It should, of course, be understood that the under spaces corresponding to those existing between words or isolated letters may 15 be formed in any suitable way, but preferably they will be formed by means of blank dies which operate to roll the metal off in substantially the manner just described.

These blank spaces may be of any uniform 20 width, or they may be of varying widths, but in all cases it is desirable to form between words, spaces of such width as to make typebars of uniform length, each having thereon a series of composed and properly spaced types whether the blank spaces 25 be of the same width or of varying widths, thus assuring the formation of typebars having types thereon properly composed and spaced.

30 Having described my invention, I claim—

1. The improved typebar herein described consisting of a longitudinally-wrought bar of metal having types wrought on its edge.

2. The improved typebar herein described 35 consisting of a longitudinally-wrought bar of metal having a series of types provided with forged bases.

3. The improved typebar herein described 40 consisting of a longitudinally-wrought bar of metal having a series of composed and properly spaced types wrought into shape thereon.

4. The improved typebar herein described 45 consisting of a longitudinally wrought bar of metal constituting the body portion of the typebar and a wrought line of type along the edge of such body portion and integrally connected therewith.

5. The improved typebar herein described 50 comprising a rolled body portion having a line of rolled type along its edge.

6. The improved typebar herein described comprising a longitudinally rolled body por-

tion having a line of rolled type along its edge.

55

7. The improved typebar herein described comprising a longitudinally rolled body portion having a line of cross-rolled type along its edge.

8. An improved typebar, consisting of a 60 longitudinally wrought bar of metal having perpendicularly wrought type upon its edge.

9. An improved typebar, consisting of a 65 longitudinally wrought bar of metal having a series of types provided with transversely forged bases.

10. An improved typebar, consisting of a longitudinally wrought bar of metal having a series of composed and properly spaced types perpendicularly wrought into shape 70 thereon.

11. An improved typebar, comprising a 75 rolled body portion having rolled type along its edge, the line of the forging of the rolling being in transverse directions.

12. An improved typebar, comprising a 80 longitudinally wrought body portion having a line of cross-rolled and perpendicularly forged type along its edge.

13. An improved typebar, comprising a 85 rolled body portion having a line of type rolled and forged in transverse directions, each of which is transversely disposed to the line in which the body was rolled.

14. An improved typebar, consisting of a 90 longitudinally wrought bar constituting the body portion thereof and a line of transversely wrought types along the edge of said body portion and integrally connected therewith.

15. An improved typebar consisting of a 95 wrought bar having the line of the grain longitudinally disposed thereof and a line of wrought type disposed along the edge of said body portion and integrally connected therewith, having the line of their grain transversely disposed to said former line.

16. An improved typebar comprising a 100 wrought body portion having a line of type along its edge wrought thereon in a direction transversely to the direction in which the body portion is wrought.
